UNITED STATES PATENT OFFICE

CHARLES WATKINS BROWN, OF SAN DIEGO, CALIFORNIA

CLOSET FLUSHING DEVICE

Application filed August 8, 1931. Serial No. 555,977.

This invention relates to no-tank flush valves for closets and the like and has particular relation to such a valve mechanism which will deliver a plurality of quantities of water, selectively, to the closet.

During periods of drought and in cities where there is a limited water supply, the attention of the public works engineers has been directed to the necessity for the adoption of all necessary means to conserve the supply of water and prevent its waste and unnecessary or unwarranted use. It has been found that a large proportion of the water used is expended in the flushing of closets. It has also been determined by experiment that much water is wasted in closet flushing which should be saved.

The closet flushing devices in common use are so constructed that they will deliver a sufficient amount of water to perform the flushing operation properly but in most instances, the amount of water is in excess of the amount needed and in some instances it is many times the required amount.

The primary object of this invention is the provision of an improved closet flushing device.

Another object of the invention is the provision of an improved closet flushing device capable of delivering any one of a plurality of amounts of water to the closet, under control of the operation.

Another and further object of the invention is the provision of a closet flushing device which has a single manually controlled means having connections to the water control means to deliver a predetermined amount of water to the closet when one movement characteristic is given to the manually controlled means and a different predetermined amount of water to the closet when a different movement characteristic is given to the manually controlled means.

Another and still further object of the invention is the provision of a closet flushing device which is provided with two valves of the "dash-pot" type and a selective control device for controlling the operation of these valves.

Other and further objects of the invention

will be apparent to those skilled in the art from a reading of the complete specification and claims.

Referring to the drawings where I have illustrated an embodiment of my invention.

Figure 1 is a front elevation of the invention.

Figure 2 is a side elevation.

Figure 3 is a cross section on the line 3—3 of Figure 2.

Figure 4 is a cross section on the line 4—4 of Figure 3.

Figure 5 is a cross section on the line 5—5 of Figure 3.

Figure 6 is a cross section on the line 6—6 of Figure 3.

Figure 7 is a view similar to Figure 3, but with one flush valve open.

Similar reference characters refer to the same or similar parts throughout the specification and claims.

The numeral 10 designates the body of the device having an inlet opening 11 and an outlet opening 12. The inlet opening 11 connects to an inlet chamber 13. The inlet chamber 13 has two openings 14 and 14' which connect to the outlet chamber 15^a which in turn connects to the outlet opening 12.

In the openings 14, 14' are located the flush control valves 15 and 15'. These valves control the starting and stopping of the flushing operation. On one side of the inlet chamber 13 and having one end exposed thereto are two cylinders 16, 16'. In these cylinders 16, 16' are located pistons 17, 17'. In order to control the movement of the valves 15, 15' from the pistons 17, 17', connecting means between the respective valves and pistons are provided as the rods 18, 18'.

Those portions of the chambers 16, 16' which are divided from the inlet chamber 13 by the pistons 17, 17' are provided with connections to both the intake space 13 and the outlet chamber 15^a for the purpose of controlling the movement of the pistons 17, 17' and in turn admitting water for flushing purposes from the inlet chamber 13 to the outlet chamber 15^a.

These connections are of two types—one for filling the chambers 16 and 16' and the other

for emptying these chambers when the valves 15, 15' are closed.

From the inlet chamber 13 extends two passages 19, 19' which connect the chamber 13 to the cylinder spaces 16, 16'. In order to control the flow of water through these passages, two adjustable control valves 20, 20' are provided. These valves may be in the form of adjustable screw valves as shown or constructed in any suitable manner.

The outlet ports from the chambers 16, 16', I have designated 21, 21'. These passages lead to a cylinder in which is located valves 22, 22'. Each of these valves in the form illustrated, has a cut-away portion which is long enough to connect the port 21 or 21' with an opening of a passage 23, 23' leading to the outlet chamber 15^a. The valves 22, 22' are controlled by springs 24, 24' which tend to force the valves to positions where the solid portion of the valve is in a place to interrupt the passage of water between the chamber ports 21, 21' and the passages 23, 23'.

In a position to operate either one of the valves 22, 22' is a lever 24 which is pivoted at 25. The lever 24 is in a position to be easily operated and may be operated to either side or to first one side and then the other in rapid succession.

The operation of my invention is as follows:

Let us assume the valves 20, 20' to be respectively set to give small and large amounts of water for flushing purposes. Under normal conditions of use, the inlet chamber 13 is under the static pressure of the water main connection to the inlet 11, the valves 15, 15' are on their seats and the pistons 17, 17' are as shown in Figure 1. Assuming the operating lever 24 to be moved to the right, the opposite end will move to the left with a consequent movement of the valve 22 to a point where the opening 21 will have communication with the passage 23 through the cut-away portion of the valve 22. As the full pressure of the water main is on the rear of the valve 15 and also on the exposed area of the cylinder 17, there will be a resultant pressure tending to open the valve 15 due to the larger area of the cylinder. This immediately causes the cylinder 16 to lose its water content as the cylinder 17 moves to force the water out through the opening 21 past the cut-away portion of the valve 22, and out through the passage 23 to the outlet chamber 15^a which empties through the outlet opening 12 to the closet.

As soon as the valve 15 leaves its seat there is a stream of water delivered to the outlet chamber equal to the capacity of the valve opening 14.

The sizes of the openings 21 and passage 23 and the cut-away portion of the valve 22 are such as to quickly open the valve 15 to its full opening. When the lever 24 is released, the

spring 24 will return the valve 22 to its normal closed position. This cuts off communication between the interior of the cylinder 16 and the outlet chamber 13. As soon as this takes place, the slow leak from the intake chamber 13 through the passage 19, past the control valve 20 and into the chamber 16, gradually moves the piston 17 to bring the valve 15 to its seat. When the valve 15 reaches its seat, the flushing operation ceases.

It is thus clear that the duration of the flushing operation determines the amount of water which is delivered. And since the amount of water passing the valve 20, determines the speed of closing of the valve 15, it is seen that the duration of the flushing operation will be determined by the adjustment of the control valve 20.

Consequently after installation, it is necessary to adjust the control valves 20 and 20' until just the proper amount of water is used in the two flushing operations controlled by these valves 20, 20'. Thus if the valve 20' is set to cause a rapid refilling of the cylinder 16' and the valve 20' is set for a slow refilling of the cylinder 16' it is clear that the valve 15' will control a small or short flush while the valve 15' will control a long flush delivering a greater amount of water.

If desirable to have even a greater amount of water than the setting of either valve 15 or 15' will cause alone, it is only necessary to operate the two valves 22, 22' in rapid succession. The combined effect of both the small and the large flushing operations is then obtained.

By this invention it is possible with a single control lever or handle to bring about a flushing operation of any one of three different amounts of water.

One important advantage of my invention is the ability to readily adjust the valves 20, 20' to obtain the exact amount of water for the particular type of installation with which it is used.

While I have illustrated and described in detail one form of my invention, I desire to have it understood that I do not limit myself to the exact disclosure and that modifications and changes may be made without departing from the spirit of the invention and within the scope of the appended claims.

Having described my invention what I claim and desire to secure by Letters Patent is:

1. A no-tank closet flushing device comprising two flush valves, each valve having an independently adjustable means for definitely controlling the amounts of water discharged from the respective valves and a single manual means operable to open one valve when one movement characteristic is given the manual means and to open the other valve when a different movement characteristic is given the manual means.

2. A no-tank closet flushing device comprising a valve means adjustable to deliver a predetermined amount of water to the closet, a second valve means adjustable to deliver a different predetermined amount of water to the closet and a single manually operable means for operating, at will, either of the valve means to admit the predetermined amount of water controlled by that valve means.

3. A no-tank closet flushing device comprising a valve, a piston for moving the valve, a cylinder for the piston, adjustable means for controlling the movement of the piston to permit the valve to admit a predetermined amount of water to the closet, a second valve, a second piston for moving the second valve and a second cylinder for the second piston, a second adjustable means for controlling the movement of the second piston to permit the second valve to admit a predetermined amount of water different from that controlled by the first valve, and a single manually operable means for operating, at will, either of the valve means to admit the predetermined amount of water controlled by that valve operated.

4. A no-tank closet flushing device comprising an inlet connection and an outlet connection, a plurality of independently operable valves between the inlet and outlet connections, a piston and cylinder for each of the valves, connections from the pistons to the valves, hydraulic connections between the inlet and the respective cylinders and adjustable means for controlling each connection independently of the other, a connection between each cylinder and the outlet connection for permitting escape of water from the cylinder, a separate control means for each cylinder connection for, at will, permitting or preventing the water from the cylinder to escape to the outlet and a single manually operable device for operating either separate control means independently of the other.

5. A no-tank closet flushing device comprising an inlet connection and an outlet connection, a plurality of independently operable valves between the inlet and outlet connections, a piston and a cylinder for each of the valves, each piston having an operative connection to its valve and being exposed on one side to the pressure of the inlet connection, and being hydraulically connected on its other side to the outlet connection, independently operable valves for controlling the hydraulic connections to the outlet connection and a single manually operable means for, at will, operating either independently operable valve alone or both in rapid sequence.

6. A no-tank closet flushing device comprising an inlet connection and an outlet connection, a plurality of independently operable valves between the inlet and outlet connections, a piston and a cylinder for each of

the valves, each piston having a rigid connection with its valve and exposed on one side to the pressure of the inlet connection and being hydraulically connected on its other side to the outlet connection, independently operable valves for controlling the hydraulic connections to the outlet connection, the independently operable valves having portions extending toward each other, a single operating lever having a portion in position to operate either independently operable valve alone or both in rapid sequence.

In testimony whereof, I hereunto affix my signature.
